J. SYLVAN

WINDOW FRAME CONSTRUCTION

Filed May 5, 1922

FIG. 3.

FIG. 4.

Inventor

Joseph Sylvan
by Clarence E. McElroy
Attest.

UNITED STATES PATENT OFFICE.

JOSEPH SYLVAN, OF CICERO, ILLINOIS.

WINDOW-FRAME CONSTRUCTION.

Application filed May 5, 1922. Serial No. 558,596.

To all whom it may concern:

Be it known that I, JOSEPH SYLVAN, a citizen of the United States, and a resident of Cicero, in the county of Cook and State of Illinois, have invented certain new and useful Improvements in Window-Frame Construction; and I do hereby declare that the following is a full, clear, and exact description thereof, reference being had to the accompanying drawings, and to the letters of reference marked thereon, which form a part of this specification.

This invention relates to improvements in window frame construction and consists of the matters hereinafter described and more particularly pointed out in the appended claims.

One of the objects of the invention is to provide a window frame which includes in one or more of its parts, a passageway for the entrance of fresh air into the interior of the room and a means for warming the air before it enters the room.

This object of the invention, as well as others, together with the many advantages thereof, will more fully appear as I proceed with my specification.

In the drawings:

Fig. 1 is a view in elevation of a window frame embodying my invention, as looked at from the inside of a room.

Fig. 2 is a horizontal sectional view on an enlarged scale as taken on the line 2—2 of Fig. 1.

Figs. 3 and 4 are detail vertical sectional views through one of the side members of the frame as taken on the lines 3—3 and 4—4 of Fig. 2.

Fig. 5 is another detail vertical sectional view through the top or lintel member of the frame as taken on the line 5—5 of Fig. 1.

Referring now in detail to that embodiment of the invention illustrated in the accompanying drawings:—10 indicates as a whole a window frame, embodying my invention. Said frame includes the upright side members 11—11, an intermediate upright mullion 12, a horizontal top member, or lintel 13, and a sill 14. Hinged to the mullion are two sash 15—15 of the casement type which are adapted to close at their outer margins against fixed parts of the side members 11—11 of the frame.

Each upright side member 11 includes a

front or inner rail 16 and a side rail 17 arranged at a right angle thereto, the outer marginal parts of each side rail terminating in an upright shoulder 18, against which the free margin of the associated sash 15 engages, when each sash is in its fully closed position. In each side rail 17 is provided a vertically elongated opening or slot 19 which is covered by a grating or screen 20 and in each front rail is provided a similar opening or slot 21 which is covered by a similar grating or screen 22. Fixed to the side rails 17 at a point spaced from and extending parallel with the front rail is an insulating strip 23. In each side frame member is an upright tubular heating element 24 which is spaced from both the inner and side rails of the frame member and engages along one margin with the insulating rail 23. In this instance the heating element forms a part of a steam heating system and to that end its bottom end is connected by a pipe 25 which may be connected in any suitable manner to the heating system of the building in which it is installed. A valve 26 is interposed in the pipe 25, said valve having a stem 27, which projects outwardly through the sill beneath its ledge so that it may be conveniently actuated to control the amount of heating medium passing through the pipe 25. To increase the superficial heating and radiating surface of the heating element 24, I provide vertically spaced ribs 28 on that side adjacent the side rail 17.

In the opening 19 of each side rail I provide vertically spaced louvre plates 29 which extend the full width of said opening. Said plates are inclined upwardly and outwardly away from the grating or screen 20 toward the heating element (see Fig. 3). In the opening 21 of each front rail 16 I provide similar vertically spaced louvre plates 30 which extend the full width of said opening. The louvre plates 30 are inclined upwardly and outwardly from the heating element toward the grating or screen 22. (See Fig. 4.) In the space between the adjacent edges of the louvre plates I provide an upright filler strip 31 which fits in the corner angle of the rails 16 and 17. (See Fig. 2.)

The air that enters the opening 19 contacts with the heating element to be warmed and then passes out through the opening 21,

the filler strip 31 preventing the air from passing directly from the one opening to the other.

The lintel 13 includes a bottom rail 32 and a front rail 33, each having an elongated opening 34 and 35 respectively therein which are covered by the associated gratings or screens 36-37. In the lintel is provided a horizontally disposed tubular heating element 38, which is connected at its ends to the like elements 24 in each upright side member of the window frame. I also provide in said lintel, a plurality of louvre plates 39, one half of which are inclined in one direction from the vertical median plane of the mullion, while the other half are inclined in an opposite direction from said median line of the mullion. On that margin of the side rails 17 adjacent the inner or front rails, I provide the upright ledges 40, the purpose of which will presently appear.

Assume that the sash 15-15 are in the closed position shown in full lines in Fig. 2 and that the heating medium is circulating through the heating elements in the frame members. It is well known that in cold weather, the air within the room in the vicinity of the window is cooled by reason of its proximity thereto. As the air in the side frame members is warmed by the heating elements, an upward movement of the air is produced, which air passes out through the outlet openings, into the room. This produces a suction action near the inlet openings, drawing the cool air therethrough. The cool air thus drawn in, becomes warmed by the heating element, and passes out through the outlet openings, thus setting up a circulation to warm the air in the vicinity of the window.

Assume it is desired to permit the entrance of fresh air from the outside atmosphere. One of the sash 15 is swung into a partly opened position as shown in dotted lines in Fig. 2 wherein its free edge is closed against the upright ledge 40. In this position of the sash, the inlet opening is connected with the outside atmosphere, but no cold air can enter the room through the window opening. The cool, fresh outside air, passes through the inlet opening, is warmed by the heating element and then passes out through the outlet opening into the interior of the room.

It will be noticed that by reason of the louvre plates, the air in its passage through the frame member is broken up and directed upwardly toward the ceiling of the room so that no direct draft enters the room when the sash is partly open, as just described. The gratings or screens covering the inlet and outlet members, hide the louvre plates from view, and add to the appearance of the frame. The construction, just described, also readily adapts itself to such standard window hardware as locks and handles and

the like and does not necessitate special hardware.

While, in describing my invention, I have referred to certain details of mechanical construction and arrangement of parts I do not wish to be limited thereto except as may be pointed out in the appended claims.

I claim as my invention:

1. In combination with a frame for window sash, said frame including upright side and mullion members and a top lintel member, one of said members being constructed to permit the passage of air therethrough and having an inlet opening and an outlet opening at a right angle thereto, means in said member between said openings for warming the air as it passes through said member, and a window sash hinged to one of said upright members to swing in a horizontal plane and adapted to close off said inlet opening from and to open the same to the outside atmosphere.

2. In combination with a frame for window sash, said frame including upright side and mullion members and a top lintel member, one of said members being constructed to permit the passage of air therethrough, and having an inlet opening arranged in a plane at a right angle to the sash and an outlet opening arranged in a plane parallel with the sash, means in said member between said openings for warming the air as it passes through said member, and a window sash hinged to one of said upright members to swing in a horizontal plane and adapted to close off said inlet opening from and to open the same to the outside atmosphere.

3. In combination with a frame for window sash, said frame including upright side and mullion members and a top lintel member, the side members being constructed to permit the passage of air therethrough, each side member having an inlet opening arranged in a plane at a right angle to the sash and an outlet opening arranged in a plane parallel with the sash, a heat radiating device in each of said side members for warming the air as it passes therethrough, and a window sash for each upright member hinged to the mullion member to swing in a horizontal plane and adapted to close off said inlet openings from and to open the same to the outside atmosphere.

4. In combination with a frame for window sash, said frame including upright side and mullion members and a top lintel member, one of said members being constructed to permit the passage of air therethrough and having an inlet opening arranged in a plane at a right angle to the sash and an outlet opening arranged in a plane parallel with the sash, louvres in each of said openings, and a window sash hinged to the mullion member to swing in a horizontal plane

and adapted to close off said inlet opening from and to open the same to the outside atmosphere.

5. In combination with a frame for window sash, said frame including upright hollow side and mullion members and a hollow top lintel member, said side members and said top member being constructed to permit the passage of air therethrough and 10 each having an inlet opening arranged in a plane at a right angle to the sash and an outlet opening arranged in a plane parallel with the sash, a heating element in each member between the inlet and outlet openings thereof, louvres in said openings for directing the air toward and away from said heating element, and a window sash for each upright member hinged to the mullion member to swing in a horizontal plane and adapted to close off said inlet openings from and 20 to open the same to the outside atmosphere.

6. In combination with a window frame, including upright side members, an upright intermediate mullion member, and a top lintel member, said side members being constructed to permit the passage of air therethrough; window sash hinged to the mullion member to swing in a horizontal plane, each of said upright side members having an air inlet and an air outlet opening which are arranged respectively in a plane at a right angle to and in a plane parallel with said sash, a heating element within each upright side member of the frame, and louvres in each opening; the sash being capable, when swung into one position, of exposing the air inlet openings to the outside atmosphere. 25 30 35

In testimony that I claim the foregoing as my invention, I affix my signature this 29th day of April, A. D. 1922.

JOSEPH SYLVAN.
